UNITED STATES PATENT OFFICE

171,261

SKILL TESTING GAME DEVICE

Jerry C. Koci, Barrington, Ill., assignor to Chicago
Coin Machine Co., Chicago, Ill., a corporation of Illinois

Application July 8, 1953, Serial No. 25,845

Term of patent 3½ years

(Cl. D34—5)

To all whom it may concern:

Be it known that I, Jerry C. Koci, a citizen of the United States, and a resident of Barrington, in the county of Lake and State of Illinois, have invented a new, original, and ornamental Design for a Skill Testing Game Device, of which the following is a specification, reference being had to the accompanying drawing forming a part thereof, and in which:

Fig. 1 is a perspective view of a skill testing game device showing my new design;

Fig. 2 is a perspective view of the same viewed from the opposite side; and

Fig. 3 is an end view of the same.

I claim:

The ornamental design for a skill testing game device, as shown.

JERRY C. KOEI.
